ATTORNEYS

UNITED STATES PATENT OFFICE.

JOHN L. GANS, OF CONNELLSVILLE, PENNSYLVANIA.

SCRUBBING-BRUSH.

SPECIFICATION forming part of Letters Patent No. 634,813, dated October 10, 1899.

Application filed November 18, 1898. Serial No. 696,773. (No model.)

To all whom it may concern:

Be it known that I, JOHN L. GANS, a citizen of the United States of America, residing at Connellsville, in the county of Fayette and State of Pennsylvania, have invented certain new and useful Improvements in Scrubbing and Cleaning Brushes, of which the following is a specification, reference being had therein to the accompanying drawings.

10 My invention relates to certain new and useful improvements in scrubbing and cleaning brushes.

The object of my invention is to provide a brush of this character which can be operated either by the pressure of water or compressed air.

A further object of my invention is to provide a brush of this character which can be used for the scrubbing of floors, decks, pavements, cleansing of windows with water, as well as removing dust, dirt, &c., from wood-work, furniture, carpets, clothing, &c.

A further object of my invention is to provide a brush of this character which is adapted for either delicate or rough work.

Briefly described, my invention comprises a circular brush having a series of turbine or deflecting plates mounted on the periphery of said brush, a supporting-bracket to pivotally support the brush, and the operation of the brush by means of water or compressed air coming into contact with the turbine or deflecting plates.

My invention finally consists in the novel combination and arrangement of parts hereinafter more fully described, and particularly pointed out in the claims.

In describing the invention in detail reference is had to the accompanying drawings, forming a part of this specification, wherein like numerals of reference indicate corresponding parts throughout the several views thereof, and in which—

Figure 1 is a side view of my improved scrubbing and cleaning brush, partly in section, showing operating means therefor. Fig. 2 is a top plan view thereof, a portion of the cover broken away, showing the turbine or deflecting plates in dotted lines. Fig. 3 is a side view of the cover, showing the apertures

formed therein for the insertion therethrough of the supporting arm or bracket, and a portion of the feed-water or air pipe. Fig. 4 is a perspective view of the supporting arm or bracket, a feed-pipe nozzle, and a portion of the handle. Fig. 5 is a longitudinal sectional view of a portion of the brush, showing the arrangement of the water-passages.

Referring to the drawings by reference-numerals, 1 indicates the back of the brush, which is substantially circular in formation, in which the bristles 2 are secured. Connected to the periphery of the back by any suitable means are a series of turbine or deflecting plates 3. These deflecting-plates may be arranged in a curvilinear manner, as shown, or they may be inclined, and are adapted to have their upper edge abut against the plate 4, which is suitably secured to the back of the brush. The plate 4 is of greater diameter than the back 1 to allow the edge thereof to project over the edge of the back. Secured to the upper face of the plate 4, at the center thereof, by any suitable means, as at 5, is an upwardly-extending interiorly-screw-threaded collar 6, which is adapted to receive the screw 7, having an enlarged head 8.

9 indicates a supporting arm or bracket for the brush, having an enlarged free end 10, which is apertured or countersunk on its upper end, as at 11. This enlarged portion is adapted to revolvably receive the collar 6, which is held in position by means of the enlarged head 8 of the screw 7, fitting into the countersunk portion 11. The opposite end of the bracket 9 is formed integral with the water or air feed pipe 12, which has a suitable nozzle 13 connected thereto to its inner end, while the opposite end thereof is exteriorly screw-threaded, as at 14, to receive the water or air supply pipe. (Not shown.) Mounted on the feed-pipe 12 is a valve or regulating-cock 15 for regulating the flow of water or air to the turbine or deflecting plates.

Formed on the periphery of the pipe 12 are a pair of supporting-brackets 16 17 for the purpose of securing therein the handle 18 for the brush by means of the set-screw 19.

20 indicates a cover or casing surrounding the brush to confine the water or air thereto

and is apertured, as at 21, to allow of the insertion therethrough of the supporting bracket or arm 9, and also apertured, as at 22, to allow of the insertion therethrough of the water or air feed pipe 12.

The back of the brush 1 has arranged there-in a series of radial water-passages 23, terminating with the periphery of said back adjacent the turbine or deflecting plates 3. Intersecting said passages is another series of axially-extending passages 24, terminating between the bristles 2, whereby water striking the turbines is deflected and caused to flow through the passages to the bristles.

15 It will be readily apparent that when the water is forced against the turbine or deflecting plates the pressure thereof will readily revolve the brush and the bristles will speedily remove all dirt or collected foreign matter 20 from the object desired to be cleaned, and owing to the arrangement of the water-passages the water will thoroughly impregnate the bristles to assist in the cleaning operation.

25 It will be noted that various changes may be made in the details of construction without departing from the general spirit of my invention.

Having thus fully described my invention, 30 what I claim as new, and desire to secure by Letters Patent, is—

1. In a cleaning and scrubbing brush, the combination of a circular back provided with interior radial water-passages and axially-extending 35 intersecting water-passages, bristles secured in said back between the axially-extending passages, a collar centrally mounted on said back, a supporting-arm revolvably connected to said collar, a series of turbines peripherally arranged on the back and adjacent the open ends of the radial passages, and a feed-pipe connected to said supporting-arm and having its discharge end in close prox-

imity to the turbines, substantially as herein shown and described.

2. In combination in a scrubbing-brush, a circular back with a series of turbines peripherally arranged thereon, said back being provided with interior radial water-passages and axially-extending intersecting water-passages, bristles secured in said back, a supporting-arm revolvably connected to said back, a feed-pipe connected to said arm and having its discharge end in close proximity to said turbines, and a cover inclosing said back and rigidly connected to said supporting-arm, substantially as herein shown and described.

3. In a scrubbing and cleaning brush, the combination of a circular back carrying the bristles, of a series of turbines peripherally arranged on said back, a supporting-arm revolvably connected to said back, a feed-pipe connected to said arm and having its discharge end in close proximity to said turbines, a handle connected to said feed-pipe, 60 and a cover inclosing the back and rigidly connected to said supporting-arm, substantially as herein shown and described.

4. In a scrubbing-brush, the combination of a circular back provided with interior radial water-passages and axially-extending intersecting water-passages, a series of turbines connected to said back adjacent to the open ends of the radial passages, a supporting-arm rotatably connected to the back, a feed-pipe connected to said arm, and a circular cover rigidly connected to the supporting-arm and extending below the circular back and its turbines for inclosing the same, substantially as herein shown and described. 75

In testimony whereof I affix my signature in the presence of two witnesses.

JOHN L. GANS.
